UNITED STATES PATENT OFFICE

ALFRED W. BRUCE, OF NEW YORK, N. Y.

LOCOMOTIVE BED

Application filed August 13, 1929. Serial No. 385,657.

This invention relates generally to locomotives, and more particularly to the frame carried by the driving wheels, and which serves as a bed or support for the body of the 5 locomotive.

In prior and present practice two types of locomotive beds have been employed, one wherein the side frames with pedestal jaws, and the cross braces constituting the axle 10 pockets are formed together as an integral casting. This type of construction often includes in the integral casting various other parts, such, for example, as the cylinder casting, cradle, pony truck center pin guide 15 casting, etc. While integral constructions are highly advantageous because of their great strength, light weight, economy of manufacture, and high factor of safety, they are open to the serious objection that the 20 machining of the pedestal jaws is a costly and expensive operation due to the excessive size of the piece of work which must be handled and to the further fact that each pedestal must be machined independently. A 25 further objection is that whenever renewal of the pedestal jaws or other parts of the integral construction is required, the locomotive structure must be dismantled. In the other type of construction the side frames, 30 cross braces, cradle, cylinder castings, etc. are formed as separate parts which must be fabricated together by bolting, riveting or welding.

Such fabricated structures possess the advantage that the pedestal jaws of six or 35 more side frames can be machined at a single operation, and the machining of the other relatively small members can be done with the ordinary machinery of the usual railroad machine shop. The fabricated constructions however, are open to the serious objections that a large amount of machining is entailed in insuring the proper fit between the parts, the excessive weight of the completed structure, the high cost involved in 40 fastening the various parts together, the inability of the structure to resist heavy strains, and the low factor of safety possessed by the completed structure.

50 An object of the present invention is to

provide a locomotive bed wherein the body member which may embody across braces, axle pockets, etc., is formed as an integral casting, and the two side frames having pedestal jaws, are separately formed and 55 bolted or otherwise fastened to the body member. Such a construction possesses the important advantage that while it enables the pedestal jaws to be economically and accurately machined, the completed structure 60 is characterized by the light weight and great strength of integral structures.

A further object of the invention is to combine with the body member in an integral or one piece casting one or more of the following parts, viz, cradle, fire box, brackets, draft pocket, combined saddle and cylinders or cylinder saddle or cylinder saddle seat, and front frame, and such other parts as have heretofore been combined in integral cast 70 beds.

A further object of the invention is to provide a locomotive bed more economical to manufacture and maintain, than the integral or the fabricated beds heretofore known, 75 which is of greater strength and less weight than the fabricated beds heretofore known, and which is of equal strength with the integral beds heretofore known. Other objects of the invention will hereinafter readily appear.

The improvement claimed is hereinafter fully set forth.

In the accompanying drawings: Figure 1 is an isometric view of a locomotive bed and 85 certain associated parts, embodying the invention, the cylinder castings being shown as detachable from the saddle, and the side frames detached from the body member; Fig. 2, a fragmentary isometric view of a modified construction wherein the cylinder and cylinder saddle are combined with the integral bed casting; Fig. 3, a fragmentary isometric view of another modified construction 90 wherein the front end of the bed is provided with a seat for a detachable cylinder saddle; Fig. 4, a vertical section, taken on the line IV-IV of Fig. 1; and, Fig. 5, a horizontal section, taken on the line V-V, of Fig. 4.

In the practice of the invention, referring 100

to the specific embodiment thereof which has been selected for exemplification herein, the locomotive bed comprises two paramount features, viz: a body member 10, formed as an 5 integral casting and two detachable side frames 10g.

The body member comprises two skeleton parallel relatively thin side walls 10a, suitably recessed to provide openings 10b, for the 10 driving axles, and cross braces 10c, of inverted channel form disposed in alignment with the openings 10b, and joining the side walls together. Each cross brace comprises a horizontal plate 10d, and two vertical skeleton plates 10e, disposed on each side of the axle openings 10b, a short distance back therefrom. Each side wall is formed at its top 15 with a longitudinal, horizontal, laterally projecting flange 10f, adapted to assist in supporting the body member on a pair of separately formed side frames 10g, which are bolted or otherwise suitably secured to the body member. Each side frame 10g, is provided with a top rail 10h, pedestal jaws 10k, 20 and lugs 10m, adapted to engage with the usual binders or tie bars. It is to be noted that the pedestal jaws extend inwardly of the sides of the axle openings 10b, when the side frames are applied so that the usual shoes 25 may properly fit the machined pedestal jaws. Important advantages of forming the side frames separately from the body member are that a plurality of the pedestal jaws may be accurately machined at one operation, without the use of special machinery, instead of machining each jaw separately as is necessary where the jaw is an integral part of a bulky one piece bed, and that the side frames can be separately detached for renewal and 30 repairs without dismantling the locomotive structure.

It is within the contemplation of the invention to form integrally with the body member 10 of the bed a cradle 11, which may have integrally formed therewith a draft 35 pocket 11a and fire box brackets 11b; a cylinder saddle 12, to which may be bolted cylinder castings, 12a; and a front extension, 12c, for a pony truck center pin guide, and bumper beam support.

In Figure 2 is illustrated a modified form of construction wherein the cylinder saddle 12 and the cylinder pieces 12a, each having a cylinder and a distribution valve chest, are integrally united in a one piece casting with the bed.

Fig. 3 illustrates a further modification wherein the forward portion of the bed is formed with a depressed seat, 12d, adapted 60 to support a detachable cylinder saddle. As has been stated the invention may be employed under suitable conditions general to locomotives regardless of their type whether articulated, non-articulated, steam, electric 65 or any other class.

While one of the preferred forms of construction has been shown, it is obvious that many variations in procedure, form, arrangement, and construction of parts can readily be made, and the invention is not therefore limited to the particular embodiment disclosed, but includes such changes and modifications as come within the spirit and scope of the invention as set forth in the appended claims. 70

The invention claimed and desired to be secured by Letters Patent, is:

1. A locomotive bed comprising a body member formed as an integral, one piece casting for carrying the load of a steam locomotive super-structure, and a pair of separately formed side members comprising pedestal jaws. 80

2. A locomotive bed comprising a body member formed as an integral, one piece casting and embodying cross braces forming axle pockets, and a pair of separately formed side frames each having pedestal jaws extending inwardly of the pockets. 85

3. A locomotive bed comprising a body member for carrying the load of a steam locomotive super-structure, said body member being formed as an integral one piece casting, a pair of separately formed side members comprising pedestal jaws, and means fastening the side frames to the body member. 90

4. A locomotive bed comprising a body member formed as an integral one piece casting and having longitudinal parallel vertical side walls formed without pedestal jaws, and embodying axle openings. 100

5. A body member for locomotive beds for carrying the load of a steam locomotive super-structure, said body member being formed as an integral, one-piece casting and comprising cross braces and vertical side walls adapted for the application of separately formed side members comprising pedestal jaws. 105

6. A locomotive bed comprising separately formed side frames, and an integral one piece casting embodying a body member and a cradle. 110

7. A locomotive bed comprising separately formed side frames, and an integral one-piece casting embodying a body member, a cradle, and brackets on the cradle for supporting a fire box. 115

8. A locomotive bed comprising separately formed side frames and an integral one-piece casting embodying a body member, a cradle and a draft pocket at the rear end of the cradle. 120

9. A locomotive bed comprising separately formed side frames and an integral one-piece casting embodying a body member, and a seat for a cylinder saddle. 125

10. A locomotive bed comprising separately formed side frames, and an integral, one- 130

piece casting embodying a body member, and a cylinder saddle.

11. A locomotive bed comprising separately formed side frames, and an integral, one-piece casting embodying a body member, a cylinder saddle, and cylinders.

12. A locomotive bed composing a pair of separately formed side members, longitudinal members extending the entire length of the side members, means for securing the side members to the longitudinal members, and cross members connecting the longitudinal members.

13. A locomotive bed comprising a pair of separately formed side members, a structure including longitudinal and cross members and longitudinal flanges, said flanges resting on the side members, and means for securing the side members to the structure.

14. A locomotive bed comprising separately formed side frames, and an integral, one-piece casting embodying a cradle, a body member, and a cylinder saddle.

15. A locomotive bed comprising separately formed side frames, and an integral, one-piece casting embodying a cradle, a body member, a cylinder saddle, and cylinders.

16. A locomotive bed comprising separately formed side frames, and an integral, one-piece casting embodying a cradle, a body member, a cylinder saddle, cylinders and distribution valve chests.

17. A locomotive bed comprising separately formed side frames, and an integral, one-piece casting embodying a body member having vertical, parallel, longitudinal side walls formed with axle openings, cross braces connecting the walls and forming axle pockets, and a seat for a cylinder saddle.

18. A locomotive bed comprising separately formed side frames, and an integral, one-piece casting embodying a body member having vertical, parallel, longitudinal side walls formed with axle openings, and cross braces connecting the walls and forming axle pockets, and a cradle.

19. A locomotive bed comprising separately formed side frames, and an integral, one-piece casting embodying a body member having vertical, parallel, longitudinal side walls formed with axle openings, and constituting means for attaching the side frames, and cross braces connecting the side walls, a cradle, and a cylinder saddle.

20. A locomotive bed comprising separately formed side frames, and an integral, one-piece casting embodying a body member having vertical, parallel, longitudinal side walls formed with axle openings, and constituting means for attaching the side frames, and cross braces connecting the side walls, a cradle, a cylinder saddle, cylinders, and distribution valve chests.

21. A locomotive bed, comprising a body member formed as an integral one piece cast-

ing, said member having side walls embodying axle openings and longitudinal plates connecting the openings, said plates being provided with bolt holes adjacent said openings; separately formed side frame members 70 embodying pedestals registering with the axle openings, said pedestals being connected by longitudinal plates each having bolt holes adjacent the sides of the pedestals to register with the holes of an adjacent plate of 75 the body member; and bolts passing through the registering holes securing the plates together.
